COMBUSTION CHAMBER

Raymond J. Dufour, Oak Park, Ill., assignor to
Autogas Corporation, Chicago, Ill., a corpora-
tion of Delaware

Application June 1, 1936, Serial No. 82,798

1 Claim. (Cl. 158—1)

This invention relates to combustion chambers, and especially those intended for use with conversion burners, and is illustrated as embodied in a radiant structure for use with a gas burner.

5 An object of the invention is to provide radiants adapted to be built up readily into combustion chambers of different shapes and sizes. Preferably the radiants are formed at their ends with surfaces which nest together to form ball-and-socket joints, or other integral pivots, permitting the combustion chamber to be built up with any desired number of sides, and of different sizes.

10 The above and other objects and features of the invention, including various novel constructions and desirable particular arrangements, will be apparent from the following description of the illustrative embodiment shown in the accompanying drawing, in which:

15 Figure 1 is a perspective view of an assembled combustion chamber, ready for use with a conversion burner;

20 Figure 2 is a perspective view of one of the radiants;

25 Figure 3 is an elevation showing the overlapping ends of the radiants, partly broken away to show the joints; and

30 Figures 4, 5, 6, and 7 are diagrammatic plan views showing different possible arrangements of the radiants.

The illustrated combustion chamber, shown generally at 10 in Figure 1, is intended for use with a conversion burner as described in Wetherbee Patent No. 1,919,285, granted July 25, 1933.

35 Gas or other fuel is burned inside the combustion chamber, the burning products of combustion issuing through slots 12 between superimposed radiant elements 14 consisting, in the form illustrated, of fluted trapezoidal-section strips of ceramic material. There may also be blank segments 16 fitting closely against each other at parts of the combustion chamber where it is not desired to generate radiant heat, as for example facing the door of the furnace.

40 The radiants 14 and 16 are built up, generally in the manner of a log cabin, with the ends of each radiant between the ends of two of the others. A top 18, also a ceramic material, covers the stack of radiants so built up over the burner.

45 50 The burning gases issuing through the slots 12

raise the radiants to incandescence, the heat being transferred to the furnace walls in straight lines as radiant heat, in the same general manner that the heat of burning anthracite is transferred to the furnace walls.

5 According to an important feature of the present invention, each radiant 14 (or 16) has on its upper and lower faces, at both ends, integral pivot means nesting with corresponding parts of the adjacent radiants. I prefer to provide such means by forming the upper face with a concave hemispherical socket 20, and the lower face with a convex hemispherical projection 22, the projection 22 on each radiant nests readily 15 into the socket 20 of the next lower radiant.

20 This construction greatly facilitates building up different sizes and shapes of combustion chambers in different furnaces. For example the combustion chamber may have four sides each 20 the length of one radiant 14 (Figure 4), or six such sides (Figure 5), or eight such sides (Figure 6), or four sides each the length of two of the radiants 14 (Figure 7).

25 The radiants illustrated have spacer shoulders 26 which determine the width of slots 12, and have longitudinal flutes 28 on their upper and lower faces, with vertical flutes 30 on their vertical faces.

30 While one particular construction has been described in detail, it is not my intention to limit the scope of the invention to that particular construction, or otherwise than by the terms of the appended claim.

I claim:

35 A combustion chamber comprising a stack formed of a series of superimposed segments arranged in layers with the adjacent ends of the segments overlapping and interconnected by ball-and-socket joints, each of said segments having 40 a convex semi-spherical projection and a concave cavity at each end in vertical alinement, said projections and cavities interfitting to form said ball and socket joints, and said segments being arranged so that there are intervening slots between the ends of the superimposed segments for the escape of gases of combustion from the interior of said chamber.
